United States Patent

Des. 238,244
Patented Dec. 30, 1975

238,244

BOTTLE OPENER OR SIMILAR ARTICLE

Michael J. Pasquale, 115 Grove St.,
Middletown, Conn. 06451

Filed May 6, 1974, Ser. No. 467,494

Term of patent 14 years

Int. Cl. D7—06

U.S. Cl. D8—18

FIG. 1

FIG. 4

FIG. 2

FIG. 3

FIG. 5

FIG. 6

FIG. 1 is a side view of a bottle opener or similar article showing my new design;

FIGS. 2 and 3 are, respectively, the top and bottom views of the bottle opener of FIG. 1;

FIGS. 4 and 5 are, respectively, the left hand and right hand end views of the bottle opener of FIG. 1; and

FIG. 6 is a side view showing the side opposite to that shown in FIG. 1.

I claim:

The ornamental design for a bottle opener or similar article, substantially as shown and described.
